WILLIAM B. GARDNER, OF ALMOND, NEW YORK.

Letters Patent No. 89,140, dated April 20, 1869.

IMPROVED WASHING-MACHINE.

The Schedule referred to in these Letters Patent and making part of the same.

To all whom it may concern:

Be it known that I, WILLIAM B. GARDNER, of Almond, in the county of Allegany, and State of New York, have invented a new and useful Improvement in Washing-Machines; and I do hereby declare that the following is a full, clear, and exact description thereof, which will enable others skilled in the art to make and use the same, reference being had to the accompanying drawings, forming part of this specification.

My invention relates to improvements in washing-machines, such as have a grooved roller, and a reciprocating curved and grooved board, acting in conjunction therewith; and

It consists in the application to the said grooved roller of a brake, arranged to arrest the motion thereof, when required, to subject some parts of the clothes to a greater amount of rubbing than other parts, as hereinafter more fully specified.

Figure 1 represents a side elevation of a machine having my improvement applied to it, and

Figure 2 represents a longitudinal sectional elevation of the same.

Similar letters of reference indicate corresponding parts.

A represents the tub, B a rotary grooved rubbing-cylinder, and C a curved grooved reciprocating board, working in conjunction with one side of the cylinder,

being actuated by a crank and connecting-rod, and forced against the cylinder or the clothes by a spring.

In the operation of this machine it is desirable to arrest the motion of the cylinder at times, to subject certain parts of the clothes to a continued rubbing action by the board C.

To this end, I provide on the axle of the cylinder a toothed wheel, as shown in dotted lines at D, and combine therewith a curved toothed brake, E, so arranged that it may be actuated either by the hand or foot, and provided with a spring, F, to hold it out of contact with the toothed wheel when not required to act thereon. The roller being operated by a belt, G, and grooved pulley, permits such stoppages, when required, without interfering with the action of the other parts.

For actuating the lever by the foot, a treadle is suspended from the end thereof by a cord or rod.

Having thus described my invention,

I claim as new, and desire to secure by Letters Patent—

The combination, with the cylinder B, of the toothed brake-wheel and brake, when arranged to be operated by the hand or foot, and provided with the spring E, all substantially as specified.
